UNITED STATES PATENT OFFICE.

SERENUS M. COLBURN, OF MINNEAPOLIS, MINNESOTA, ASSIGNOR OF ONE-HALF TO
FREDERICK KEEES, OF MINNEAPOLIS, MINNESOTA.

DESIGN FOR A STREET-LIGHT STANDARD.

43,796.

Specification for Design.

Patented Apr. 1, 1913.

Application filed February 15, 1913. Serial No. 748,735. Term of patent 7 years.

To all whom it may concern:

Be it known that I, SERENUS M. COLBURN, a citizen of the United States, residing at Minneapolis, in the county of Hennepin and State of Minnesota, have invented a new, original, and ornamental Design for a Street-Light Standard, of which the following is a specification, reference being had to the accompanying drawings, forming part thereof.

Figures 1 and 2 are views in elevation showing different sides of a street light

standard embodying the improved design, some parts of Fig. 1 being removed to show the central upper portion of the standard; and Fig. 3 is a bottom plan view of the upper portion of the street light standard.

I claim:

The ornamental design for a street light standard, as shown.

SERENUS M. COLBURN.
